UNITED STATES PATENT OFFICE.

WILLIAM P. RUBLE AND WILLIAM B. STEVENS, OF ESMOND, NORTH DAKOTA.

GRAIN-CAR DOOR.

1,275,477.

Specification of Letters Patent. Patented Aug. 13, 1918.

Application filed February 27, 1917. Serial No. 151,248.

To all whom it may concern:

Be it known that we, WILLIAM P. RUBLE and WILLIAM B. STEVENS, both citizens of the United States, and both residing at 5 Esmond, in the county of Benson and State of North Dakota, have invented certain new and useful Improvements in Grain-Car Doors, of which the following is a specification.

10 This invention relates to doors of the kind employed on grain cars and which are so constructed and mounted that they may be raised and lowered as required and may while being lowered be moved in guides beneath the car floor in such manner as to hold the top or upper edge of the door at any desired elevation while the lower portion of the door is moved entirely out of sight and out of the way.

15 The object of our invention is to provide novel and efficient means for connecting the door sections with each other and for raising and lowering them.

The door which we employ is constructed 20 of a series of sections having their upper and lower edges hinged together and these sections are adapted to be moved in guides arranged vertically in the doorway and which are extended beneath the floor of the 25 car. The door sections are formed with teeth on their opposite edges with which engage worms that are mounted to turn about vertical axes and which are operated by worms carried by a horizontal shaft extending from one side of the doorway to the other and provided with a crank, hand wheel, or other suitable means for turning it. The organization is such that comparatively little friction is produced while the 30 door is being raised and lowered. The vertical worms operate in opposition to each other and raise the door without putting any strain or pressure on the guides and therefore the door may be raised and lowered with a minimum expenditure of power 35 and with great facility. Worms are of course more powerful than ordinary sprocket gearing and by having the worms engage teeth on the opposite ends of the door sections pressure or friction which would otherwise be produced is eliminated.

In the accompanying drawings,

Figure 1 shows in elevation a portion of a grain car to which our improved door is applied. Some parts are shown in section, some in dotted lines and other parts are

broken away in order to more clearly illustrate the invention.

Fig. 2 shows a horizontal section on the line 2—2 of Fig. 1. 60

Fig. 3 shows a vertical section on the line 3—3 of Fig. 1.

Fig. 4 is a detail view on an enlarged scale and on the section indicated by the line 4—4 in Fig. 1. 65

Fig. 5 is a view on an enlarged scale showing two sections of the door and illustrating how the sections are hinged together and how they are formed with teeth at their edges. 70

Fig. 6 is a perspective view on an enlarged scale of portions of two of the door sections and indicates how these sections are grooved vertically.

The car body as a whole is indicated by 75 A, the car floor being shown at a. The doorway is provided on opposite sides with runways or guides B for the car door D and these guides are continued or extended beneath the floor a, as shown most clearly 80 in Fig. 3.

The door D is composed of a series of slats or sections d, hinged to each other at their upper and lower edges. Preferably these sections are made of sheet metal, the 85 lower portion of each section being formed with a socket d', which receives the upper portion of an adjacent section which is enlarged by being bent or doubled upon itself as indicated at d''. The construction as will 90 be observed is such that the sections may be readily connected and disconnected when required. When they are arranged vertically, as indicated in Fig. 3, they cannot 95 separate, but if one section be moved to a position at right angles to the other section the two sections may be separated. When the sections are passing through the curved portion b of the guides B the walls of the guide hold the sections in place so that they 100 cannot separate. The manner in which this is done is indicated in Fig. 3. The hinged joints d', d'' do not extend from one end of the sections to the other and do not enter the vertical portions of the guides B. By 105 reference to Fig. 1 it will be seen that the hinged parts d' and d'' are much shorter than the section and the opposite ends of the sections extend into the guides B in the manner more clearly indicated in Fig. 2. 110

The guides are provided with vertical flanges b' which enter the vertical grooves

*d*³ in the sections. This provides a tight fit which will prevent leakage of grain. When the door is raised to the position shown in Figs. 1 and 3, the doorway is 5 tightly and securely closed and is sufficient for all purposes although the door may be used in connection with an outer door if desired.

The mechanism for raising and lowering 10 the door comprises worms E mounted on vertical shafts e supported in brackets e'. The worms are so mounted that they engage the teeth *d*⁴ on the opposite ends or vertical edges of the door sections. The 15 shafts e carry worm wheels F with which engage worms G on a horizontal shaft H supported in brackets h and which extends from one side of the doorway to the other. Said shaft may be provided with a crank I, 20 a hand wheel J, or any other suitable operating mechanism. By merely turning the shaft H the door may be raised and lowered with great facility, the thrust of the worms E being endwise in each section and both 25 the worms operating to raise the door in a vertical direction without exerting pressure between the door sections and the guides.

We claim as our invention:

1. A car door provided on each opposite 30 side edge with a vertically arranged series of teeth, in combination with worms mounted to turn about vertical axes and which engage the two series of teeth for raising and lowering the door.

2. A car door provided on each opposite 35 side edge with a vertical series of teeth, worms mounted to turn about vertical axes and engaging the two series of teeth for raising and lowering the door, and means for simultaneously operating said worms. 40

3. A car door provided on each opposite side edge with a vertical series of teeth, worms mounted to move about vertical axes and engaging said teeth for raising and lowering the door, a horizontally arranged 45 operating shaft and gearing between said shaft and said worms whereby they are simultaneously operated.

4. A car door made in sections hinged together at their upper and lower edges and 50 having vertically arranged teeth at their opposite ends, guides in the sides of the doorway and beneath the car floor in which the sections move, worms mounted to turn about vertical axes and engaging the toothed 55 ends of the door sections, a horizontally arranged operating shaft, and worm gearing between this shaft and the vertically arranged worms which raise and lower the car door.

In testimony whereof we have hereunto subscribed our names.

WILLIAM P. RUBLE.
WILLIAM B. STEVENS.
